CLAIM

The ornamental design for a case, as shown and described.

DESCRIPTION

FIG. 1 is a front perspective view of the case.

FIG. 2 is a top plan view thereof; the bottom plan view

thereof being mirror image of the view shown in FIG. 2;

FIG. 3 is a front elevation view thereof;

FIG. 4 is a rear elevation view thereof;

FIG. 5 is a right side elevation view thereof, the left side elevation view thereof being mirror image of the view shown in FIG. 5; and,

FIG. 6 is a front perspective view of the case showing the lid in an open position.

The broken lines in the figures are shown for illustrative purposes only and form no part of the claimed design.
